CLAIM

The ornamental design for a tow eye cover, as shown and described.

DESCRIPTION

FIG. 1 is a front, right perspective view of a tow eye cover showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

A second embodiment of the claimed design for the tow eye cover is a mirror image of the tow eye cover as shown in FIGS. 1 to 7.

1 Claim, 4 Drawing Sheets(56)
